UNITED STATES PATENT OFFICE.

BELLE M. SAHLEIN, OF SAN FRANCISCO, CALIFORNIA.

PORTABLE SOUND-LOCALIZER.

1,245,514.

Specification of Letters Patent.

Patented Nov. 6, 1917.

Application filed March 20, 1917. Serial No. 156,102.

To all whom it may concern:

Be it known that I, BELLE M. SAHLEIN, a citizen of the United States, residing in the city and county of San Francisco and State of California, have invented new and useful Improvements in Portable Sound-Localizers, of which the following is a specification.

My invention relates to a means for localizing sounds and preventing their escape beyond the immediate region where they are produced. It is especially designed for use in connection with telephones which may be established in offices, rooms, or departments of stores, where other noises prevail, and where it is desirable to maintain secrecy in the transmission of messages.

It consists of a portable cage, so constructed as to admit the head and shoulders of the operator, and of material which will so deaden the sound, that the voice of the operator, or the substance of what is conveyed by him cannot be understood.

Referring to the accompanying drawings for a more complete explanation of my invention—

Figure 1 is a perspective, exterior view of the device.

Fig. 2 is a perspective view of the interior frame.

Fig. 3 is a fragment, showing the collapsing joint.

Fig. 4 is a perspective view of a non-collapsible cage.

In department stores there are frequently a number of distinct departments located near together and upon the same sales counter. In offices, also, it is often necessary to have communication through a telephone while other clients may be seated in the office, where it is desirable that the visitors should not hear the conversation.

For this purpose it is desirable to have some means for preventing the escape of sound from the immediate neighborhood of the telephone. Such a means I have provided in the form of collapsible cage A, which may be made of any suitable light material, such as a wire frame of sufficient size to admit the head and shoulders of an operator, and this frame may be covered with felt, baize, or be provided with double walls of any suitable deadening material. The cage may also be made entirely of felt or fiber material, of any suitable kind, which will prevent the escape of sound. The device may be provided with celluloid or simi-

lar transparent openings at the side and front, as at 2, and the rear portion may be open and have a flexible curtain or curtains 3 so disposed as to fall over the shoulders of the user, when in use.

This device is light and may be easily moved from one end of a desk to the other, or from one desk to another; the telephone receiver being connected by a suitable cord 65 which allows it to be moved around the room or department where it is located. The cage will have a sufficient opening or means at 4 by which the cord can be passed into it with the receiver and transmitter inside of the 70 cage, so that it will be possible to move the cage to any convenient or desired point within the room or department, and connect the cord with the cage where the operator may then conduct the conversation in such a 75 manner that it will not be audible from the outside.

In order to enable the cage to be collapsed into a small space, when not in use, the vertical rods 5 of the cage are jointed and have 80 loops 6 formed at the ends, each loop inclosing the straight part of its companion rod, upon which it is slidable to collapse the cage. A latch 7 is formed upon one member to engage the other, so as to retain the cage in an 85 extended condition.

Having thus described my invention, what I claim and desire to secure by Letters Patent is—

1. In a sound localizer for telephones, a 90 frame including a lower section having a head receiving opening in its bottom, an upper section slidably connected to the lower section so as to be capable of moving vertically toward and away from the latter, 95 means to hold the sections against collapsing, and a fabric covering extending over the top of the upper section and over the sides of both sections, said covering having a back extension projecting below the frame bottom to engage over the shoulders of the user.

2. In a sound localizer for telephones, a frame including an upper and a lower section each having vertical overlapping rods, 105 each of said rods having an eye slidably receiving the rod of the other respective section, latches carried by the rods of one section and engageable with the eyes of the other section to hold the sections against 110 sliding, and a covering for the sections.

3. In a sound localizer for telephones, a

wire frame having a top, sides and an open bottom, the bottom wire being arched upwardly at the front thereof to admit the receiver and transmitter cords, and a covering 5 for the top, sides and front of the frame, said covering having an extension at the back of the frame projecting below the frame bottom to engage over the shoulders.

In testimony whereof I have hereunto set my hand in the presence of two subscribing 10 witnesses.

BELLE M. SAHLEIN.
